UNITED STATES PATENT OFFICE.

WALTER KENNEDY, OF PITTSBURG, PENNSYLVANIA.

COKING APPARATUS.

No. 831,163.

Specification of Letters Patent.

Patented Sept. 18, 1906.

Application filed February 1, 1905. Serial No. 243,685.

To all whom it may concern:

Be it known that I, WALTER KENNEDY, of Pittsburgh, Allegheny county, Pennsylvania, have invented a new and useful Coking Apparatus, of which the following is a full, clear, and exact description, reference being had to the accompanying drawings, forming part of this specification, in which—

Figure 1 is a plan view of apparatus embodying my invention. Fig. 2 is a vertical section on the line II II of Fig. 1. Fig. 3 is a similar view showing the parts in another position. Fig. 4 is an end elevation of the apparatus for transferring the coked charge to railway-cars, and Fig. 5 is a plan view thereof.

In the drawings, 2 2' represent beds on which my movable ovens 3 rest during the operation of coking. The ovens are set thereon in parallel rows, between which extends at a lower level a track 4, upon which the cars 5 5' run, which receive and carry away the coked contents of the ovens. Above the rows of ovens is a traveling crane 6, mounted on a track 7 parallel with the rows of ovens and having a bridge 8, carrying trolleys 9 10, provided with hoists for raising and lowering the ovens for handling the lid 11, which is set over the hot mass of coke on the car 5, and for carrying the movable bin or hopper 12, from which the coal to be coked is fed. The bridge also has a drum 13, from which chains or ropes 14 14' extend transversely for attachment to the oven, enabling the oven to be moved laterally to and from the coking-bed.

The ovens are masonry structures, as shown by dotted lines in Fig. 2, inclosed in strong metal shells or casings and are provided with lugs 15 for engagement with hooks 16, which depend from the lifting-trolley 9. These hooks are pivoted at 16' to cross-bars 16", which render the device flexible and easy to engage.

Fig. 3 shows one of the ovens 3' in the operation of being charged with coal and a second oven 3 in which the charge has been coked, having the lifting-chains applied to it and in readiness to be shifted laterally to the car.

To charge the empty oven 3', bins or hoppers 12 are filled with coal and brought opposite to the oven on the car 5. One of them is then raised by the hoisting mechanism on the trolley 10, is moved on the bridge directly above the oven 3', and its content of coal is then discharged directly into the oven, this

operation being repeated as often as needed to fill the oven to the required extent. The coal in the oven is then coked in the usual way.

When a charge has been coked, it is then removed onto the car 5'. (Shown in Fig. 2.) For this purpose the hooks 16 are brought into engagement with the oven 3 which contains the coked charge, the car 5' is brought opposite to the oven 3, and its bed or platform 17 is shifted so as to be flush with the bed 2 on which the oven rests, as shown in Fig. 2. For this purpose I prefer to make the bed 17 shiftable laterally on the axles of the car by means of bell-crank levers 18 or otherwise. The oven is then raised slightly by lifting the hooks 16, so as to clear it from frictional contact with the coking-bed 2, and by drawing on the chain 14 the oven is shifted laterally, dragging the body of coked coal with it until the coke is deposited upon the platform of the car 5'. The oven is then raised clear of the mass of coked coal, leaving the latter resting on the car, as shown at 19 in Fig. 2. The trolley 9 is then moved back over the bed 2, and the oven is lowered into the original position, (shown in Fig. 3,) where it is in readiness to receive another charge of coal. The lid 11 is then moved over the body of hot coke on the car 5' and is lowered so as to cover and inclose the same and prevent loss of coke by combustion, and the car is then drawn off and the hot charge of coke quenched and discharged into railway-cars.

I prefer to discharge the coke into railway-cars by the use of the apparatus shown in Figs. 4 and 5. For this purpose the car 5', carrying the mass of coke covered by the lid, is conveyed on its track to a point under an elevated crane bridge 20 on which there is a trolley 21, adapted to be moved back and forth along the bridge by means of a suitable motor 22. The trolley carries a depending lifting-frame 23, having hooks or other devices 24 for engaging lugs 25 on the lid 11. When the car carrying the coked charge is brought opposite to the lifting device 23, the latter is moved along its track until the hooks 24 come opposite to the projections 25, and at this point the wheels of the trolley 21 reach a raised portion 26 of its track, which lifts it somewhat, and thus elevates the lid 11 slightly above the platform of the car. Further motion of the lifting-crane 23 will then carry the lid 11 laterally over the railway-car 27, onto which the coked charge of coal then

drops, and water can be immediately discharged on the coke to quench it in the car, or it may be quenched before it is discharged from the lid by admitting water into the lid.

- 5 For the purpose of carrying off from the oven gases formed by the coking of the coal I prefer to arrange in the beds 2' 2' underground flues 28, leading to a stack and having projecting pipes 29, provided with suitable valves, preferably of the well-known Spearman type, said pipes being adapted to register with the flue-openings 30, formed in the oven, so that when the ovens are brought into position on the coking-bed they will automatically come into registry with the pipes 29, which will then draw off and deliver to the stack-flue 28 the gases formed by the coking operation.

By proceeding in this manner the cost of handling the coal and coke and of moving the oven is reduced to a minimum and I am enabled to realize to the best advantage the benefits obtained by coking the coal repeatedly on a hot bed without chilling the oven or injuring its structure by the operation of drawing and quenching in the oven heretofore commonly practiced.

I claim—

1. Coking apparatus, comprising the combination of coking-beds, movable ovens mounted thereon, and a traveling lifting device having pendent flexible supports adapted to grasp and lift the ovens from the beds and flexible means connected with said supports for shifting the ovens laterally; substantially as described.

2. Coking apparatus comprising the combination of coking-beds, movable ovens mounted thereon, a traveling lifting device having pendent flexible supports adapted to grasp and lift the ovens from the bed and flexible means connected with said supports for shifting the ovens laterally, and a car adapted to travel along the line of such ovens and to receive the coked mass; substantially as described.

3. Coking apparatus, comprising the combination of coking-beds, movable ovens mounted thereon, a traveling lifting device, and chains or ropes extending over the beds

transversely to the oven and adapted to shift it laterally; substantially as described.

4. Coking apparatus, comprising the combination of coking-beds, movable ovens mounted thereon, a traveling lifting device having flexible means extending over the beds adapted to grasp the ovens to lift and shift them, and means on said lifting device for handling a charging-hopper for delivering coal to the oven; substantially as described.

5. A coke-oven movable to and from the coking-bed, and a gas-exit flue extending below the bed of the oven adapted to register with the oven when the latter is in coking position; substantially as described.

6. Coking apparatus comprising a coking-oven, means for moving the body of coke as a mass onto a car, a lid for covering the coked mass, and a shifting device for shifting the lid on the car and carrying the coke therefrom, and discharging it into a car or other receptacle; substantially as described.

7. Coking apparatus comprising a coking-oven, means for moving the body of coke as a mass onto a car, a lid for covering the coked mass, and a shifting device for shifting the lid on the car and carrying the coke therefrom and discharging it into a car or other receptacle, said shifting means being adapted to raise the lid from the bed of the car; substantially as described.

8. Coking apparatus comprising a coking-oven, means for moving the body of coke as a mass onto a car, a lid for covering the coked mass, and a shifting device for shifting the lid on the car and carrying the coke therefrom and discharging it into a car or other receptacle, said shifting means being mounted on a track provided with an elevated portion adapted to raise it and to elevate the lid from the body of the car; substantially as described.

In testimony whereof I have hereunto set my hand.

WALTER KENNEDY.
